UNITED STATES PATENT OFFICE.

CHARLES O. ELLERT, OF BROOKLYN, NEW YORK.

CENTERING APPARATUS FOR CONCRETE CONSTRUCTION.

1,317,564.

Specification of Letters Patent. Patented Sept. 30, 1919.

Application filed February 27, 1914, Serial No. 821,575. Renewed March 8, 1919. Serial No. 281,545.

To all whom it may concern:

Be it known that I, CHARLES O. ELLERT, a citizen of the United States, and a resident of the city of New York, borough of Brooklyn, county of Kings, and State of New York, have invented certain new and useful Improvements in Centering Apparatus for Concrete Construction Carried or Supported by I-beams or like Members, of which the following is a full, clear, and exact description.

This invention relates to apparatus used in the construction of plastic or concrete pavements or floors or the like carried or supported by steel I beams or like members.

The object of this invention is to provide an improved centering apparatus for positioning and supporting plastic or other suitable material used to construct pavements or floors or like structures to be carried by I beams or like members, and adapted to be readily positioned, dismantled or re-positioned adjacent suitable I beams, without injury to the members or parts of said centering apparatus.

Another object is to provide an improved adjustable clamping or holding means engaging suitable I beams and suitable longitudinal bearing or supporting members of said centering apparatus, whereby said bearing members are adapted to have a range of vertical adjustment limited by means provided in said clamping means, and also to provide a means co-acting with said clamping or holding means whereby said clamping means may be readily detached and removed from said I beams when adjacent concrete has set or hardened.

With these and other objects in view, the invention consists in the novel construction and arrangement of parts hereinafter described and pointed out in the claims, reference being had to the accompanying drawing forming a part of the specification, in which similar reference characters indicate similar parts.

Figure 1, is an elevation showing the collapsible centering apparatus applied to I beams.

Fig. 2, is a perspective of one of the clamping members of the collapsible clamping or holding means shown in Fig. 1, show-

ing means to permit vertical movement or adjustment of the longitudinal bearing members of the apparatus.

Fig. 3, is a perspective of means for uniting or joining the separable clamping members shown in Fig. 2, to form the collapsible clamping means and also adapted to join or connect the meeting ends of abutting bearing members.

Fig. 4, is an enlarged detail elevation of auxiliary clamping means for positioning suitable panel carriers upon the bearing members.

Fig. 5, is a central vertical cross section of parts of clamping means shown in Fig. 4.

Suitable I beams are indicated by the numeral 1.

The longitudinal bearing members 2, are provided, if desired, with longitudinal holding means 3, shown as a recessed means, similar to that shown in panel supporting members 22, where a recessed holding means 23^b, is provided with suitable angle irons 24, 75 along its holding edge by screws 25.

Said recessed holding means 3, are adapted if desired, to engage an auxiliary detachable clamping device comprising, a plate 18, similar to 31, Fig. 1, having on its inner face an upward extending flange 18^a, Fig. 5, adapted to engage the longitudinal holding means 3, and on opposite face of plate 18, is provided a bearing 17, Figs. 4 and 5, similar to 30, Fig. 1, for a clamp lever 16, similar to 29, Fig. 1, which is held in position on bearing 17, by a suitable washer 20, and a suitable threaded nut 21, is secured on the threaded end 17^a, of the bearing 17; said clamp lever 16, is provided with suitable interlocking means, as openings 16^a, 16^b, adapted to register with openings 19, 19^a, 19^b, in plate 18, Fig. 4; openings 32, Fig. 1, being similar to openings 19, 19^a, 19^b.

At 15, similar to 28, Fig. 1, a lever 14, similar to 27 is pivoted to the clamp lever 16, and is provided with a threaded upper end 14^a, Fig. 4, fitted into a threaded recess 13^b, in clamp member 13, similar to 26, Fig. 1; this member 13, is provided with a downwardly extending flange 13^a, similar to 26^a, Fig. 1, which is adapted to engage the recessed holding means 23^b, of the panel sup-

porting members 22 while the upwardly extending flange 18^a, is adapted to engage the recessed holding means 3.

The panel supporting members 22, are positioned upon and transversely to said bearing members 2 and have a slidable adjustment thereon.

The clamp jaw or cap member 13, and the plate 18, form the opposite members 10 of the auxiliary clamping device, and the panel supporting members 22, are drawn against the bearing members 2. The said panel supporting members 22, are preferably positioned intermediate the adjoining I 15 beams and are adjusted to any point between said I beams as desired.

The said bearing members 2 are removably secured to I beams by an adjustable and removable clamping means comprising, a 20 pair of opposing clamping members and co-acting means to construct an adjustable and collapsible clamping means.

In Fig. 2, is shown a perspective of one 25 of the opposing clamping members; each opposing clamping member is preferably U-shaped and is provided with the vertical members 77, 77^a; slots 79, 80, in alinement with each other, are provided respectively in said vertical members 77, 77^a, with opening 30 of said slots facing each other; clamp jaws or grips as 78, 78^a, are provided respectively to the upper ends of the members 77, 77^a, and the lower or bottom ends of said members 77, 77^a, are united or joined by a connecting horizontal portion or member 78^c, 35 or similar means, having slot 81, opening upward and in alinement with said slots 79, 80. The jaws or grips 78, 78^a, may have sharpened points to be driven into wood 40 beams to secure members 2.

The said U-shaped clamping members are 45 preferably positioned in pairs, members opposing each other, to inclose and support within the U-shape, the longitudinal bearing members 2, and engage with said I beams, in a manner so that the said jaws or grips as 78, 78^a, of the said clamping members, bear upon and engage the flanges of the I beams.

50 Detachably secured pins, bolts or screws 85, are entered through slots 79, 80, of the clamping members 77, and also through slots 82, of the opposing clamping members 77^b, and suitably secured to the longitudinal bearing members 2. Said pins or bolts may 55 pass through said slots 79, 82, and if desired, transversely through said bearing members 2.

The said slots permit the bearing members 60 to have a vertical slidable reciprocal movement limited by the range of the said slots, and the holding means are adjustably secured to the bearing members by the said pins or bolts 85.

The said adjustable clamping means are 65 thus prevented from slipping away from or off the said I beams when the wedges are removed, and the removal of the pins or bolts 85, permits the clamping means to be removed from the bearing members. The 70 bearing members 2 are adjustably positioned and have a vertical slidable or reciprocal movement within the U-shaped clamping members 77, 77^a, limited by slots as 79, 82, respectively. 75

Suitable wedges 86, 87, are positioned to bear on the under or lower face or edge of said bearing members 2, and upon the connecting horizontal portion or member similar to 78^c, Fig. 2, of the opposing clamping 80 members 77, 77^b, and are driven home to firmly secure and lock the said bearing members 2 to suitable I beams, against any movement during the operation of concrete pavement or floor construction.

Suitable screws or like means 88, 89, are entered through slots similar to 81, Fig. 2, and are secured to said wedges in a manner to prevent any movement or loosening of said wedges, and also to prevent any movement of the lower portions of the opposing U-shaped clamping members. 85

A modification in construction of the adjustable clamping means is attained by providing oppositely disposed U-shaped clamping means 91, 91^b, positioned in a manner, similar to that heretofore described regarding clamping members 77, 77^b. 95

Meeting ends of the bearing members 2, 2^a abut at a point intermediate said clamping members 91, 91^b; engaging said clamping members 91, 91^b, and parallel to the bearing members 2, 2^a, is positioned a clamp connecting means 95, provided with openings 95^a, 95^b, 95^c; opening 95^a, is adapted 100 to register with slot 94, of the clamping member 91^b and opening 95^c is adapted to register with slot 93, in clamping member 91. 105

Suitable pins, bolts or screws 97, similar 110 to 85, heretofore described are entered through said registering openings and secured to, or pass transversely through said longitudinal bearing members 2, 2^a; 96 are suitable screws or bolts passing through openings 95^b, in the clamp connecting means 115 95, and detachably secured to the abutting ends of the bearing members 2, 2^a.

The said adjustable clamping means are 120 prevented from slipping away from or being accidentally displaced from the I beams; the bearing members 2, 2^a, are adjustably and removably positioned and have a vertical slidable reciprocal movement within the U-shaped clamping members 91, 91^b, limited by the range of the slots 93, 94, respectively. 125

A supplemental clamp connecting means 98, similar to connecting means 95, may be provided and adapted to be detachably se-

cured to the bottom or horizontal member as 78^c, of the opposing clamping members 91, 91^b, by suitable bolts 100, passing through slots positioned similar to slot 81, 5 Fig. 2, and a threaded nut 101, is positioned and tightened on said bolts 100.

The wedges 86, 87, heretofore mentioned engaging opposing clamping members 77, 77^b, also prevent, similar to means 98, any 10 movement to the lower portion of said members 77, 77^b.

Suitable wedges 99, are positioned to bear against the under or lower faces of the bearing members 2, 2^a, and are adapted to rest 15 upon the bottom or horizontal portion or member as 78^c, of the U-shaped opposing clamping members 91, 91^b, and are driven home to firmly secure and position said bearing members 2, 2^a, to said I beams, against 20 any displacement during the operation of pavement or floor construction.

To provide for the ready removal of the jaw members of the clamping or holding means 77, 77^b, 91, 91^b, from the set concrete 25 adjacent the I beams and said jaw members, suitable blocks 44^b, 44^c, are adapted to be detachably positioned outside the rear faces 30 of said jaw members in a manner upon the removal of said blocks 44^b, 44^c, a void space or opening in the set concrete is provided 35 adjoining the said jaw members of a size sufficient to permit said jaw members to be removed from the flanges of the embedded I beams and enter into the said void space or opening and then removed out of and away from the set concrete. The openings in the set concrete may be filled with plastic at a later time.

A resting or elevating block 90, preferably 40 intermediate opposing clamping members, are provided between the bottom faces of the lower flanges of the I beams and the bearing members 2, or the centering or mold panels supported by said bearing members 45 2, to position said I beams at a desired distance above the bearing members 2, to permit the plastic to completely embed said I beams at all points on said I beams except at the resting or elevating blocks 90, 50 which blocks are readily removed when the centering apparatus is dismantled and the openings left in the set concrete are readily filled with plastic at a later time.

The longitudinal auxiliary panel supporting means 22, are provided with suitable recessed holding means 23^b, similar in form and construction to that in bearing members 2, and provided with suitable angle irons 24 along the holding edge secured 55 by screws 25, and are adapted to engage with a suitable auxiliary clamping means 31, 26, in a suitable manner.

The panel carriers 22, are adapted to detachably and removably position suitable

studs 33^a, braces 37^a, and mold panels or 65 centering 33^b, 34^a, 36^a, at any desired points along said I beams, in a manner whereupon the displacement of said panel carriers 22, permits the ready removal of the said mold panels or centering, without injury to any 70 of the parts or members used in the centering apparatus.

In operation, the bearing members 2 are of suitable length, and are positioned preferably transversely to and under the said 75 I beams; the adjustable removable clamping means are positioned to engage the bearing members 2, and the flanges of the I beams at suitable points; longitudinal panel carriers 22, are placed upon the bearing members 80 2 preferably parallel to and positioned intermediate said I beams; and suitable mold panels are mounted upon said panel carriers; auxiliary clamping devices are positioned and engage said panel carriers 85 and said bearing members at desired points. The longitudinal bearing members 2, 2^a, may be readily removed by the collapsing and removal of the adjustable clamping or holding means from the flanges of the I 90 beams.

Having thus fully described my invention, what I claim is:—

1. Centering apparatus for use in connection with I beams or like members, consisting of a plurality of bearing members, removable holding means provided with slotted vertical side portions engaging and connecting said bearing members and said I beams, removable means positioned in said bearing members and adapted to extend laterally outward and through said slotted vertical side portions of said holding means whereby said bearing members are adapted to have a vertical slidable reciprocal movement relative to said slotted vertical side portions, means to detachably lock said bearing members and said holding means in position, and mold panels supported by said bearing members. 95 100 105 110

2. Centering apparatus for use in connection with I beams or like members, consisting of a plurality of bearing members, removable holding means provided with jaws and slotted vertical side portions engaging and connecting said bearing members and said I beams, removable means positioned in said bearing members and adapted to extend laterally outward and through said slotted vertical side portions of said holding means whereby said bearing members are adapted to have a slidable reciprocal vertical movement relative to said slotted vertical side portions, means to detachably lock said bearing members and said holding means in position, means positioned outside the rear faces of the jaw members of said holding means to mold a cavity into which 115 120 125

said jaw members may be withdrawn from the set concrete, and mold panels supported by said bearing members.

3. Centering apparatus for use in connection with I beams or like members, consisting of a plurality of bearing members extending transversely under said I beams, a plurality of panel carriers positioned transversely upon said bearing members, holding means having slotted vertical side portions engaging said bearing members and said I beams, removable means positioned in said bearing members and adapted to extend laterally through said slotted portions of said holding means, means to detachably lock said holding means in position, and panel members mounted upon said panel carriers.

4. Centering apparatus for use in connection with I beams or like members, consisting of a plurality of bearing members, removable holding means engaging said bearing members and said I beams, means to detachably lock said bearing members and said holding means in position, panel members positioned by said bearing members in operative relation to said I beams, and means positioned outside the rear faces of jaw members of said holding means to mold a cavity into which said jaw members may be withdrawn from the set concrete.

5. Centering apparatus for use in connection with I beams or like members, consisting of a plurality of bearing members extending transversely under said I beams, removable holding means engaging said bearing members and said I beams, panel members positioned by said bearing members in operative relation to said I beams, means to detachably lock said bearing members and said holding means in position, means positioned outside the rear faces of jaw members of said holding means to mold a cavity into which said jaw members may be withdrawn from the set concrete, and removable spacing members positioned under and adjacent the bottom flanges of said I beams and intermediate holding means positioned in oppositely disposed relation to each other.

6. Centering apparatus for use in connection with I beams or like members, consisting of a plurality of bearing members extending transversely under said I beams, a plurality of panel carriers disposed upon and transversely to said bearing members, removable means engaging and connecting said bearing members and said I beams, removable means engaging said bearing members and said panel carriers permitting a slidable adjustment of the panel carriers along the upper face of the bearing members, and panel members mounted upon said panel carriers.

7. Centering apparatus for use in connec-

tion with I beams or like members, provided with removable holding means engaging said I beams and having slotted vertical side portions, and bearing members engaging said holding means and provided with removable means adapted to extend laterally through said slotted side portions whereby said bearing members are adapted to have a vertical slidable reciprocal movement relative to said slotted side portions of said holding means.

8. Centering apparatus for use in connection with I beams or like members, provided with removable holding means engaging said I beams and having slotted vertical side portions; bearing members engaging said holding means and provided with removable means adapted to extend laterally through said slotted vertical side portions whereby said bearing members are adapted to have a vertical slidable movement relative to said slotted side portions, and means positioned outside the rear faces of jaw members of said holding means to mold a cavity into which said jaw members may be withdrawn from the set concrete.

9. Centering apparatus for use in connection with I beams or like members, provided with holding means having vertically disposed slotted or like means and engaging said I beams, bearing members engaging said holding means and provided with lateral detachable means positioned in said bearing members adapted to extend laterally outward from said bearing members and engage said holding means in a manner whereby said bearing members are adapted to have a vertical slidable reciprocal movement relative to said holding means, and wedges to detachably position said bearing members.

10. Centering apparatus for use in connection with I beams or like members, consisting of a plurality of bearing members, holding means engaging said bearing members and said I beams, lateral detachable means positioned in said bearing members and adapted to extend outwardly from said bearing members and engage said holding means in a manner whereby said bearing members are adapted to have a vertical slidable movement relative to said holding means, means to detachably lock said bearing members in position, and panel members together with co-acting means supported by said bearing members.

In testimony whereof, I have signed my name in the presence of two witnesses.

CHARLES O. ELLERT.
